A. G. COE'S,
Nail Wrench.

No 11,208.

Patented July 4, 1854.

Fig. 2

Fig. 1

UNITED STATES PATENT OFFICE.

AURY G. COES, OF WORCESTER, MASSACHUSETTS.

IMPROVEMENT IN SCREW-WRENCHES.

Specification forming part of Letters Patent No. 11,208, dated July 4, 1854.

To all whom it may concern:

Be it known that I, AURY G. COES, of Worcester, in the county of Worcester and State of Massachusetts, have invented a new and useful Improvement in the Screw-Wrench or "Coach-Wrench," as it is commonly termed; and I do hereby declare that the same is fully described and represented in the following specification and the accompanying drawings, letters, figures, and references thereof.

Of the said drawings, Figure 1 denotes a side view of my improved wrench. Fig. 2 is central and longitudinal section of it.

The hammer or stationary jaw is seen at A, as permanently fixed on the top of the shank B. The movable jaw is seen at C, it being adjusted to the shank, so as to be capable of sliding freely on it. The said shank B may be made with two of its opposite sides parallel to each other, while the other two below where the sliding jaw slides, and down to a partition, Y, are made as curved cylindrical arcs, on which and above the partition Y a tube, G, is placed, the said tube being caused to embrace the shank and rotate freely on it. In the middle of the tube is a milled head, H, while on the outer surface of the tube and above the said milled-head a screw, I, is cut, and with its thread running in a direction opposite to that of a screw, E, which is formed on the external surface of that part of the tube G which is below the milled head H. The said screw-nut I receives and screws through a female screw-nut or annulus, K, that is connected to the sliding jaw C by an arm, N, as seen in the drawings. The male screw E plays into a female screw, F, that is formed within a socket-tube, P, that is so fastened to the shank B by means of the part Q of the handle, the screw-nut S thereof, and the partition Y, which extends around the socket-tube, and part of the tube and shank projecting below it, as seen in Fig. 2. The tube I constitutes a part of the handle D, the remainder of which may be made of wood, as seen at Q.

By grasping the handle D and rotating the tube G in one or the other direction the sliding jaw may be made to advance toward or recede from the hammer jaw. This movement of the sliding jaw is faster than the longitudinal motion of the tube G on the shank B, and is compounded of such move-

ment of the tube G and the longitudinal movement of the annulus K on the screw I of the tube G.

The above method of constructing a coach-wrench renders the instrument very strong and durable, and much more so than that described in Letters Patent of the United States, numbered 9,945, and granted to me on the 16th day of August 1853.

The extension of the tube G below the milled head H and into the handle contributes much to relieve the shank from being strained and injured between the handle and milled head.

The constructing a wrench with a jaw fixed to a bar (making part of or attached to a handle) and with a movable jaw made to slide on the bar and moved either toward or away from the fixed jaw by means of male and female screws is a very old device. So the employment of a pawl and a rack to adjust the sliding jaw in position is very old, and are by no means claimed by me.

By inspection of my improved wrench it will be seen that it in no respect involves the principle of combining with a wrench in which the inner jaw slides on a bar permanently attached to the outer jaw and making part of or permanently attached to the handle, a screw-thread and nut connecting the movable jaw with the said bar between the said movable jaw and that part of the handle grasped by the operator. Nor does my wrench embrace the principle or the arrangement of forming a screw on two circular edges of the flat bar to which the hammer-jaw is affixed. In my wrench there is no screw-cut on the main bar; nor is the movable jaw connected to the bar by a screw and nut, for in my wrench the screws connect the handle and the sliding jaw, while the handle is separate from and is connected to the bar back of or below the screws, and carries a socket-tube, P, having a female screw cut in it, such tube making part of the handle.

My improved wrench as above specified may be said to have the same combination of parts as is claimed in my said Letters Patent, my present invention being a new arrangement of some of the elements of such combination; consequently a patent covering my present invention will be subordinate to the former patent, and the subject of it can only

be made, sold, or used with the license of those holding that patent.

What I claim is—

The arrangement of the elevating-screw E, (made as a male screw) of the tube G on the external surface of the tube and so as to extend below the milled head H, and the screw I, in combination with the arrangement of the screw F (made as a female screw) within a

socket tube, P, on the handle, substantially as specified.

In testimony whereof I have hereunto set my signature this 23d day of February, A. D. 1854.

AURY G. COES.
